L. L. RINEHART AND P. PHILLIPS, OF EVANSBURG, OHIO.

Letters Patent No. 74,002, dated February 4, 1868.

IMPROVEMENT IN DEVICE TO PREVENT HOGS FROM ROOTING.

The Schedule referred to in these Letters Patent and making part of the same.

TO ALL WHOM IT MAY CONCERN:

Be it known that we, L. L. RINEHART and P. PHILLIPS, of Evansburg, in the county of Coshocton, and State of Ohio, have invented a new and improved Snout-Cap; and we do hereby declare that the following is a full and exact description of the same, reference being had to the accompanying drawings, and to the letters of reference marked thereon.

This invention consists of an improved device, which we call a snout-cap, intended to prevent hogs from rooting, and is so constructed as to be readily attached without piercing or cutting the snout, as is usually the case, as will be fully described. In the drawings—

Figure 1 represents a perspective view of our invention, and

Figure 2 a view of the cap attached to the animal.

A represents a strip or band of iron, or other suitable material, provided at each end with the arms α α' , curved in suitable form to fit the snout of a hog. B represents a belt or strap, preferably of rubber, securely fastened to the strip A at the proper point, and furnished with a buckle, b, by means of which the cap is securely attached to the face of the animal. C represents a piece of spring-metal, attached to the strip A at the point c, and provided at c' with a pin, which ordinarily rests in the hole α^2 , properly located for that purpose in the strip A. When this spring rests in its natural position, the free end of the pin is drawn up within the hole α^2 , so that the under surface of the strip is perfectly smooth, but when pressure is applied to it it readily yields, and the pin is forced through and beyond the hole. D represents a roller supported by the arms d.

The operation of our invention is as follows: The cap having been firmly attached to the face of the hog, by means of the rubber belt having been buckled above his tusks, he is allowed to run at will. Upon his endeavoring to root he will be foiled by the roller D, which, instead of entering the ground, will roll over it. In attempting to push through a fence, as is common with the animal, the throwing up of the snout will bring the rail in contact with the spring C, which being pushed down, the pin enters his snout and acts as an effectual preventive to future operations of that kind.

We do not claim broadly the idea of using a roller to prevent rooting, for we know that has been used before; but

What we do claim, and desire to secure by Letters Patent, is—

The strip A, with arms α α' , belt B, spring C, pin c', arms d, and roller D, when combined and arranged substantially as described.

This specification signed and witnessed, this ninth day of December, 1867.

L. L. RINEHART,
P. PHILLIPS.
